US00D885372S

(12) **United States Design Patent** (10) **Patent No.:** **US D885,372 S**
Wang (45) **Date of Patent:** **** May 26, 2020**

(54) **PAIR OF WIRELESS HEADSETS**

(71) Applicant: **Shenzhen Shengxingwang Precision Technology Co., Ltd.**, Shenzhen, Guangdong Province (CN)

(72) Inventor: **Baoqing Wang**, Shenzhen (CN)

(**) Term: **15 Years**

(21) Appl. No.: **29/667,639**

(22) Filed: **Oct. 23, 2018**

(51) LOC (12) Cl. **14-01**

(52) U.S. Cl.

USPC **D14/223**

(58) **Field of Classification Search**

USPC D14/223, 205; D24/174; 128/865, 866, 128/867; 181/129, 130, 135; 379/430, 379/431; 381/380, 381, 328, 323; 455/90.3, 575.1, 569.1

CPC H04R 1/10; H04R 25/00; H04R 1/1016; H04R 1/1066; H04R 5/033; H04R 5/0335

(57) **CLAIM**

The ornamental design for a pair of wireless headsets, as shown and described.

DESCRIPTION

FIG. 1 is a perspective view of a pair of wireless headsets showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict environment that forms no part of the claimed design.

1 Claim, 7 Drawing Sheets
